UNITED STATES PATENT OFFICE.

WALTER E. SUTTON, OF OAKLAND, CALIFORNIA, ASSIGNOR OF FORTY-TWO ONE-HUNDREDTHS TO JOHN R. SUTTON, OF OAKLAND, CALIFORNIA.

CREEPER.

1,105,008.

Specification of Letters Patent.

Patented July 28, 1914.

Application filed February 3, 1913, Serial No. 745,918. Renewed March 30, 1914. Serial No. 828,390.

To all whom it may concern:

Be it known that I, WALTER E. SUTTON, a citizen of the United States, residing at Oakland, in the county of Alameda and 5 State of California, have invented certain new and useful Improvements in Creepers, of which the following is a specification.

This invention relates to an improved form of creeper adapted to be worn on the 10 soles of boots or shoes to enable the wearer to obtain an effective tractive engagement or foothold with the surface over which he may be running or walking.

It is one of the objects of my invention to 15 provide a creeper of light and simple construction which may be readily applied and removed and which will conform and lie flat against the bottom face of the boot or shoe so that its application thereto will not prove 20 a hindrance to the wearer.

My invention will be more fully described in connection with the accompanying drawings, and will be more particularly pointed out in and by the appended claims.

25 In the drawings:—Figure 1 is a bottom face view of a boot or shoe with the device of my invention applied thereto. Fig. 2 is a rear end view of a creeper embodying one form of my invention. Fig. 3 is a side edge 30 view of one of the creeper strips.

Like characters of reference designate similar parts throughout the different figures of the drawings.

As illustrated, my invention comprises 35 companion creeper strips 1 and 2, which in the preferred construction, are disposed in crossed relation with respect to each other and diagonally across the sole 3 and shank so as to extend from opposite sides of mid-way longitudinal points of the sole toward 40 and abreast of the shank 4. The forward terminals of the strips 1 and 2 are provided with bent up ends 5, 6 and 7, 8, respectively, to form sole margin engaging lips. The 45 rear terminals have their ends bent up, as indicated at 9, 10 and 11, 12, respectively, to provide shank engaging lips. It will be readily seen by reference to Fig. 2 that the sole and shank engaging lips are arranged 50 to extend abreast of the edge of these parts and to overhang the upper margins so as to provide a firm grip engagement therewith. In order to further provide a firm engagement, I arrange the strips 1 and 2 in such a 55 manner that they will engage the sole and

shank on opposite sides, or in other words, forwardly and rearwardly of the usual outwardly curved portions 13 and 14 so as to prevent any longitudinal slipping of the strips. 60

Each strip is provided with an opening which is preferably in the shape of a letter F, as indicated at 15 and 16, and a pivot 17, which may be a loosely disposed rivet, unites the strips, as will be seen by reference to 65 Figs. 1 and 3. The greater lengths of the openings, as indicated at x, x', are disposed in the direction of the length of the sole, when the strips are in place, and they are so positioned in the strips as to be located in 70 the manner shown. The extensions x² and x³, are adapted to register or lie in overlapping relation. The extensions x² and x³ are preferably of the same length as indicated in the drawing but one may be shorter 75 than the other if desired in order to accommodate a boot or shoe of special shape. When the strips are removed from the boot or shoe the pivot can be adjusted to either lie in the short extension x² or in the long 80 extension x³, thereby altering the range of gripping action for different sizes of footwear. If the pivot is in the short extension x², the creeper will be adjusted for relatively smaller sized footwear, whereas if the 85 pivot is in the larger extension x³ the creeper will be adapted for larger sized footwear, as will hereinafter more fully appear. Pointed calks or any suitable tractive projections 90 may be provided on the bottom faces of the strips to prevent the wearer's feet from slipping.

The rear ends of the strips are provided with depending lugs 19, the flanges on both strips being identical, and each lug may be 95 provided with a bolt head engaging lip 20. Oppositely threaded bolts 21 and 22 are loosely disposed in openings in the said lugs and the polygonal heads of the bolts engage the lips 20 so as to prevent rotation of the 100 bolts. An oppositely tapped sleeve 23 is threaded on the bolts and is provided with openings 24 whereby the sleeve may be turned to draw the bolts inwardly and tighten the shank gripping lips against the 105 opposite edges of the shank and the sole gripping lips against the opposite edges of the sole. The tightening means hereinbefore described will lie close to the shank and at a point above the plane of tread, as indi- 110

cated at 2, so as not to encumber the wearer by engagement with the tread surface. The strips are curved transversely to the plane of their flat faces so as to conform to the 5 curvature of the bottom face of the sole and shank thereby permitting the strips to lie in close flat relation against the bottom of the foot gear.

In order to dispose the crossing point of 10 the strips in advance of the juncture of the shank with the sole and between the ends of the strips, I preferably curve the strips in opposite directions transversely with respect to their edges and I thereby bring the 15 tractive calks 18 across that portion of the sole which is in most effective engagement with a plane of tread, either in running or walking or when the user is pulling a load. By this disposition of the strips I 20 also advance the crossing points so as to get the most effective leverage in gripping the shank and sole terminals with the footgear.

While I have herein shown and described one specific embodiment of my invention I 25 do not wish to be limited thereto except for such limitations as the claims may import.

I claim:

1. A creeper for boots comprising in combination, companion creeper strips disposed 30 in crossed relation and each extending diagonally from a longitudinal midway point of the margin of the sole on one side of the boot across to the opposite side thereof abreast of the shank, the terminals of said 35 strips having sole and shank margin engaging lips and being curved transversely to the plane of their sides to conform to the

curvature of the bottom face of the sole and shank thereby lying flat thereagainst, said strips being also curved transversely in opposite directions with respect to their edges to dispose the crossing point in advance of the juncture of the shank and the sole, each strip being provided with an F shaped opening affording relatively long and short 45 registering terminals, a pivot in said openings arranged to be shifted from the long to the short terminals or vice versa to vary the range of grip of the strips, and means connected with the shank ends of 50 the strips for gripping the shank and sole terminals of the strips with the boot substantially as described.

2. A creeper for boots comprising in combination, companion creeper strips disposed 55 in crossed relation and each extending diagonally across the sole from one side of the boot to the other, the terminals of said strips having sole and shank margin engaging lips and each strip being provided with an F shaped opening affording relatively long and short registering terminals, a pivot in said openings arranged to be shifted from the long to the short terminals or vice versa to vary the range of grip of the strip, and 60 means connected with the strip for tightening the same upon the boot.

In testimony whereof I affix my signature in presence of two witnesses.

WALTER E. SUTTON.
